UNITED STATES PATENT OFFICE.

ARTHUR J. BERGERON, OF NEW YORK, N. Y.

ROPE-LOCK FOR PULLEYS.

1,346,696.

Specification of Letters Patent.

Patented July 13, 1920.

Application filed October 2, 1919. Serial No. 328,000.

To all whom it may concern:

Be it known that I, ARTHUR J. BERGERON, a citizen of the United States, residing at New York, in the county of New York and State of New York, have invented new and useful Improvements in Rope-Locks for Pulleys, of which the following is a specification.

This invention relates to safety devices or attachments for pulleys and more particularly to a rope lock for the same.

One of the principal objects of the invention is to provide a simple and effective lock of the class described which is adapted to be attached to the fall element of a tackle, said lock automatically functioning to grip the rope when the same moves therethrough in one direction.

Another object in view is to provide means for temporarily rendering the lock inoperative, said means being adapted to be controlled by a person on the ground through the medium of the free end of the rope which may be manipulated to accomplish this purpose.

Another object is the provision of means for rendering the locking means inactive, the same being especially adapted to be employed on tackle used in connection with scaffolding to prevent a person on the ground from tampering with the safety mechanism with a view of rendering the same inactive temporarily.

With these and other objects in view, the invention resides in the novel construction, combination and arrangement of parts, more fully described and illustrated in the following description and accompanying drawings, and particularly pointed out in the following claims.

While there has been described and illustrated a single and preferred embodiment of the invention, it is to be understood that no limitation is necessarily made to the precise details of construction, but that changes and alterations which fall within the scope of the appended claims may be resorted to when found desirable.

In the drawings:

Figure 1 is an enlarged sectional view through a fall block showing the invention applied thereto, and illustrating in dotted lines the position of the jaws and coöperating parts when they are actively engaging the rope.

Fig. 2 is a plan view of the same.

Fig. 3 is a side elevation showing the invention applied to a tackle and illustrating the safety catch thrown to its position for limiting the downward movement of the jaws.

Fig. 4 is a similar view illustrating the catch in a position to limit the upward movement of the jaws when the "block and block" arrangement of the tackle is used.

Referring to the drawings by characters of reference, 10 designates the fall block of a tackle to which is applied the supporting frame 11, said frame including horizontal and vertical side bars 12-12 and 13-13, the latter being preferably secured to the eye of the hook 14, by means of spaced rivets passed through said bars on opposite sides of the eye. The horizontal bars 12-12 are preferably secured to the opposite sides of the block by passing a bolt through openings therein which are registered with the shaft openings in the block and pulley wheel, the said bolt being used in lieu of the usual shaft. The side bars 13-13 are secured to each other by a rivet 15, from which is pivotally suspended the U-shaped yoke 16, the bight of which constitutes a jaw 17. A transverse rivet 18 is passed through the vertical side bars 12 in relative spaced relation with respect to the rivet 15 and pivotally suspended therefrom is a second U-shaped yoke member 19, the inner face of the bight of which constitutes a jaw 20. The free end of the yoke 16 is adapted to work between the side branches of the yoke 19 and is guided in its movements through the medium of a pair of spaced trunnions 21 formed on and extending from opposite sides of the yoke 16, for embracing engagement with the upper and lower surfaces of the side branches of the yoke 19. By this construction it will be seen that an upward movement of the yokes will cause relative movement of the jaws 17 and 20 toward each other for the purpose of setting up a binding action on the rope. When the tackle is used as a hoist, the mechanism acts as a safety device for the reason that sudden retrograde movement of the rope between the jaws will tend to raise the yokes, thereby moving the jaws relatively toward each other for binding the rope therebetween.

In order to provide means for temporarily rendering the gripping jaws inactive, to allow of a free movement of the rope in

2

a reverse direction whereby the fall block may be lowered, a locking mechanism for retaining the jaws in relative spaced relation is illustrated and comprises a latch member 22, pivoted on a transverse rivet 23 passing through the side arms of the yoke 16 adjacent its bight, said latch member is cut away at its free end to provide a hook 24, for engagement with the rivet 18.

10 In order to provide means for regulating the latch member whereby it may be controlled from the ground by the free end of the rope, a gravity pawl 25 is provided, the same being pivoted on a transverse rivet 26 passed through the vertical side bars 13. The gravity pawl is preferably of V-shaped formation and the extremity 27 of its upper arm is adapted to normally contact with the rivet 18 to prevent the cut away portion of the latch from engaging over the said rivet every time the jaws are moved up and down. When it is desired to render the gripping jaws inactive by effecting the engagement of the latch with the rivet 18, the rope is manipulated in such a manner as to lift the jaws until they assume the position shown in dotted lines in Fig. 1. The jaws are then allowed to slowly gravitate until the nose 28 of the latch engages the extremity 27 of the pawl. Further downward movement will lift the pawl sufficiently to allow the cut away portion 24 to engage over the rivet 18. The inner face 28^a of the nose will lock the yokes against upward movement, as the pivot 23 must necessarily move away from the rivet 18 when the yokes move upwardly. Ordinarily the jaws move down rapidly and the latch moving at the same rate of speed causes the nose 28 to jump over the extremity of the gravity pawl so that the cut away portion of the latch fails to engage the rivet. In order to effect disengagement of the hook from the rivet, the rope is manipulated to cause the yokes to gravitate to the position substantially as illustrated in Fig. 4. By this action the rivet 23 tends to move toward the rivet 18, at the same time forcing the inclined face 24^a against the rivet thereby lifting and turning the latch until the nose 28 moves over the extremity 27 of the pawl. It will therefore be seen that by the construction and arrangement herein before described, it is possible for a person on the ground to control the device by the rope, even though the fall block has been elevated to a position well out of reach.

Where the device is used in connection with tackle for scaffolding it has been found necessary to provide means located on the device which can only be controlled by a person on the scaffold and use is therefore made of a safety catch 29, pivoted at 30 to one of the side arms of the yoke 19. The catch is provided with a stop lug 31 formed by the inturned portion. Said stop lug is

adapted to coact with the trunnions 21 to selectively limit the movement of the yokes respectively up or down. When the latch is thrown to the position illustrated in Fig. 3, the lug 31 will permit of movement of the yokes in an upward direction only. The limit of the downward movement is such as to prevent the latch 22 from engaging with the rivet 18. When it is desired to arrange the tackle in what is known as a "block and block" arrangement, the catch 29 is thrown to the position illustrated in Fig. 4 and in this position the stop lug is arranged to coact with the trunnions 21 to limit upward movement of the yokes, in order that the fall block 10 may be pulled down by the free end of the rope which has been previously engaged over the hook 14.

What is claimed as new is:—

1. A rope lock comprising a pair of pivotally hung coöperating jaws, means for permitting free movement of the rope therebetween in one direction and for automatically locking the rope against movement in the opposite direction, and means for locking said jaws in spaced apart relation to permit of free movement of the rope in either direction, and for locking said rope against movement in either direction.

2. A rope lock including a pair of pivotally hung coöperating jaws, means for permitting free movement of the rope therebetween in opposite directions and for locking the rope against movement in either direction.

3. A rope lock comprising a supporting member, a pair of coöperating rope gripping jaws, each mounted on a swinging arm, said arms pivotally mounted in spaced apart relation in said member whereby the raising and lowering of said arms relative to their pivot points causes a relative movement of the jaws toward and from each other to grip or release the rope, and means for restricting the opening movement of said jaws.

4. A rope lock comprising a supporting member, a pair of coöperating rope gripping jaws, each mounted on a swinging arm, said arms pivotally mounted in spaced apart relation in said member whereby the raising and lowering of said arms relative to their pivot points causes a relative movement of the jaws toward and from each other to grip or release the rope, and means for restricting the closing movement of said jaws.

5. A rope lock comprising a supporting member adapted to be attached to a pulley block, a pair of coöperating rope gripping jaws, an arm carrying each jaw pivoted at one end in spaced apart relation to said member, means for guiding one jaw on the arm of the other jaw, and means for locking said jaws relative to each other to control their closing movement.

6. A rope lock comprising a supporting

- member, a pair of arms pivoted thereto in spaced relation, coöperating rope gripping jaws mounted on said arms at their free extremities, means on one of said arms co-
5 operating with the remaining arm to cause relative movement of the jaws toward and away from each other when the arms are raised or lowered and means for restricting the upward movement of the arms. 20
- 10 7. A rope lock comprising a supporting member, a pair of arms pivoted thereto in spaced relation, coöperating rope gripping jaws formed on said arms at their free extremities, means on one of said arms co-
15 operating with the remaining arm to cause 25

relative movement of the jaws toward and away from each other when the arms are raised or lowered, means for restricting the upward movement of the arms and a device pivotally mounted on the supporting mem- 20
ber having a portion normally obstructing the operation of the restricting means, said device being adapted to be engaged by and lifted to an unobstructing position by the restricting means when the arms are lowered slowly. 25

In testimony whereof I have affixed my signature.

ARTHUR J. BERGERON.
